UNITED STATES PATENT OFFICE.

OTTO HEBESTREIT, OF COLORADO SPRINGS, COLORADO.

TRAY.

No. 903,377.

Specification of Letters Patent.

Patented Nov. 10, 1908.

Application filed March 14, 1908. Serial No. 421,119.

To all whom it may concern:

Be it known that I, OTTO HEBESTREIT, a citizen of the United States, residing at Colorado Springs, in the county of El Paso and State of Colorado, have invented a new and useful Tray, of which the following is a specification.

This invention relates to trays, such as used by waiters for carrying dishes to and from a table when serving meals, and has for its object to provide a device which will carry a number of dishes conveniently and with safety.

Another object of this invention is to facilitate the work of removing the dishes and table utensils after each course of the meal. This is especially desirable at banquets and the like, where the entire table is to be cleared of dishes, knives, forks, and so forth, after each course. It frequently happens in such cases that the pantry is far distant from the dining room and the trays mostly used by waiters are capable of holding but a few dishes at a time, with the result that the greater part of the time devoted to such occasions is taken up by removing the dishes. The present invention aims to overcome this defect both from the standpoint of the guests and the caterer and employs a number of trays upon which dishes may be piled, and independent receptacles for knives, forks, and so forth. This arrangement will smooth affairs in the dining room and hasten those in the pantry, each tray arriving at the latter place to contain the used dishes separate from the silver.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings:—Figure 1 is a perspective view of the device. Fig. 2 is a horizontal sectional view disclosing a means by which the trays are linked together. Fig. 3 is a plan view of one of the trays.

Similar numerals of reference are employed to indicate corresponding parts

throughout the several figures of the drawings.

In the present construction, a plurality of trays, preferably formed of metal or other suitable material, are of approximately triangular form in marginal contour, and have disposed on their upper faces 1 and flanking the sides thereof a metallic rod 2, constituting a wall projecting a slight distance above the plane of each tray. The upper face of each tray has a central depression as at 3, extending transversely and from this depression is disposed a metallic strap 4 terminally secured to the upper face of the tray on the opposite sides of the depression, thus forming a pocket. A similar pocket 6 is formed at the edge of each tray in the same plane with the central pocket. The tray is further provided with elongated perforations 5 on two sides thereof and diametrically opposite each other, the function of which will appear later.

Disposed on the lower face of each tray, and directly underlying the central and side pockets 3 and 6 are folding legs. These legs are preferably formed of metal in two sections of unequal lengths with eyes on the opposed ends thereof for the reception of pivot bolts 9 by which the sections are held connected. The shorter section of each leg is soldered or otherwise secured to the lower face of each tray, and the larger section has a portion adjacent its free end turned at right angles, the turned portions 10 facing each other and adapted to enter the pockets 3 and 6, thus connecting the trays, as shown in Fig. 1.

Encircling the pivot bolts 9 are coiled springs 11 having their terminals secured to the opposed sections and normally tend to fold the sections 7 and 8 against the lower face of each tray, as shown in Fig. 2. In this construction it is obvious that the trays may be used connected, as shown in Fig. 1, in which form they are intended for use at banquets, or the like, or they may be detached and used as in the ordinary way, as shown in Fig. 3. The receptacles 12 disposed on either side of the device are preferably formed of heavy tin, galvanized iron or the like, and are in the form of oblong cans having a flat rear wall and side walls disposed at an obtuse angle thereto. The front wall is slightly arched. Intermediate disposed on the exterior of the rear

walls of each receptacle and adjacent the upper end is secured a fastener 13 which is adapted to fit within the perforations 5 formed on either side of the trays 1. This 5 construction renders the receptacles detachably secured to the device, so that when the latter is taken to the pantry and the trays filled with used dishes and the receptacles containing the used knives, forks, and so 10 forth, the latter may be removed from the trays and the contents emptied into the cleaner. This will save considerable over the old way where the silver and plates were 15 taken to the pantry in one tray, and there separated.

What is claimed is:—

1. A waiter's device embodying a plurality of trays each having foldable legs disposed on the center and one edge thereof.
- 20 2. A waiter's device embodying a plurality of trays each having legs disposed on the center and one edge thereof and adapted to be yieldingly held in normal position in contact with the trays.
- 25 3. A waiter's device embodying a plurality of trays, each having pockets on the center and one edge thereof, and foldable legs

adapted to engage said pockets and maintain the parts in spaced relation.

4. A waiter's device embodying a plurality 30 of trays, means at the center and one edge thereof connecting the same, and receptacles disposed on either side of the device and detachably secured thereto.

5. A waiter's device embodying a plurality 35 of trays, each having foldable legs combined with the center and one edge thereof, and oblong receptacles disposed on either side of the device.

6. A waiter's device embodying a plurality 40 of trays, each having pockets on the center and one edge thereof, foldable legs adapted to engage said pockets and maintain the trays in spaced relation, and oblong receptacles for table utensils detachably secured to the de- 45 vice.

In testimony that I claim the foregoing as my own, I have hereto affixed my signature in the presence of two witnesses.

OTTO HEBESTREIT.
